UNITED STATES PATENT OFFICE.

CROWEL M. DISSOSWAY, OF NEW YORK, N. Y., ASSIGNOR TO THE CO-OPERATIVE BUILDING PLAN ASSOCIATION, OF SAME PLACE.

DESIGN FOR THE EXTERIOR OF A HOUSE.

SPECIFICATION forming part of Design No. 20,098, dated August 12, 1890.

Application filed July 15, 1890. Serial No. 358,841. Term of patent 7 years.

To all whom it may concern:

Be it known that I, CROWEL M. DISSOSWAY, of New York city, in the county of New York and State of New York, have invented and produced a new and original Design for the Exterior of a House, of which the following is a specification, reference being had to the accompanying drawings, forming a part thereof.

10 Figure 1 represents a perspective view of a house showing my design. Fig. 2 represents a horizontal section or plan of the first story. Fig. 3 represents a horizontal section or plan of the second story.

15 Similar letters of reference designate corresponding parts in all the figures.

A house of this design consists of a first story and a second or attic story with a gable roof, the front having a polygonal bay to the first story and a projecting flat-faced portion at the rear thereof surmounted by a shed

25 roof, a portion of the front of the first story being taken up by a re-entrant porch, all as hereinafter to be more particularly described in detail with reference to the drawings.

20 A B designate the exterior of the first and second or attic stories, the said attic story being contained in a gable roof extending lengthwise thereof. The front has a polygonal bay D, the outer face of which is substantially 30 flush with the gable of the roof C. The rear has a projecting portion E to the first story, surmounted by a shed roof e. A re-entrant porch F is contained within the first story and forms the main entrance to the house. 35

What I claim as my design is—

The design for the exterior of a house, substantially as herein shown and described.

CROWEL M. DISSOSWAY.
